Primary Examiner — Carla J Wright

(57) **CLAIM**

The ornamental design for a phone case, as shown and described.

DESCRIPTION

FIG. 1 is a front, right-side, and bottom perspective view of a first embodiment of a phone case showing my new design; FIG. 2 is a rear, left-side, and top perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an exploded front, right-side, and bottom perspective view showing the components of the first embodiment of the phone case separated for clarity of disclosure; FIG. 10 is an enlarged view of portion 10 shown in FIG. 1; FIG. 11 is front, right-side, and bottom perspective view of a second embodiment of the phone case; FIG. 12 is a rear, left-side, and top perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; FIG. 19 is an exploded front, right-side, and bottom perspective view showing the components of the second embodiment of the phone case separated for clarity of disclosure; and, FIG. 20 is an enlarged view of portion 20 shown in FIG. 11. The dashed broken lines in the drawing figures form no part of the claimed design and depict portions of the phone case that form no part of the claimed design. The dot-dash broken lines in FIGS. 1, 10, 11, and 20 form no part of the claimed design and delineate portions of the claimed design that are shown on an enlarged scale in FIGS. 10 and 20.

1 Claim, 20 Drawing Sheets
